US0D1070497S

(12) **United States Design Patent** (10) **Patent No.:** **US D1,070,497 S**
(45) **Date of Patent:** **** Apr. 15, 2025**

(54) **BASKET SET**

(71) Applicant: **Suncha Technology Co., Ltd**, Zhejiang (CN)

(72) Inventors: **Wei Zhu**, Zhejiang (CN); **Yingjie Lin**, Zhejiang (CN); **Xixian Chen**, Zhejiang (CN); **Hao Wang**, Zhejiang (CN); **Jiaofei Shao**, Zhejiang (CN); **Lixue Zhu**, Zhejiang (CN)

(**) Term: **15 Years**

(21) Appl. No.: **29/912,035**

(22) Filed: **Sep. 12, 2023**

(51) LOC (15) Cl. **07-04**

(52) U.S. Cl.

USPC **D7/505**; D7/543; D7/667; D10/46.2

CLAIM

The ornamental design for a basket set, as shown and described.

DESCRIPTION

FIG. 1 is a front, top perspective view of a basket set, showing my new design;

FIG. 2 is a rear, bottom perspective view thereof;

FIG. 3 is a front elevational view thereof, the rear elevational view being a mirror image of FIG. 3;

FIG. 4 is a left side view thereof;

FIG. 5 is a right side view thereof;

FIG. 6 is a top plan view thereof; and,

FIG. 7 is a bottom plan view thereof.

The broken lines show portions of the basket set that form no part of the claimed design.

1 Claim, 7 Drawing Sheets
